UNITED STATES PATENT OFFICE.

GEORGE W. KNIGHT, OF HOPEDALE, MASSACHUSETTS, ASSIGNOR TO GEORGE DRAPER & SONS, OF SAME PLACE.

YARN-SEPARATOR FOR SPINNING-MACHINES.

SPECIFICATION forming part of Letters Patent No. 426,282, dated April 22, 1890.

Application filed December 17, 1889. Serial No. 334,051. (No model.)

To all whom it may concern:

Be it known that I, GEORGE W. KNIGHT, of Hopedale, county of Worcester, State of Massachusetts, have invented an Improvement in 5 Yarn-Separators for Spinning-Machines, of which the following description, in connection with the accompanying drawings, is a specification, like letters on the drawings representing like parts.

10 This invention has for its object to improve the supports for separators, so that they may be readily adjusted both longitudinally and vertically with relation to the spindle and bobbins thereon, to thus enable the separators 15 to be properly applied to any usual spinning-machine and be put in correct working position with relation to the spindles and bobbins, this adjustment being necessary because of variations in distances between the 20 usual spindles and the roller-beam of different machines made in different manufacturers.

My invention consists in a separator having a slotted supporting-arm combined with 25 a slotted stand, and with a bolt extended through the slots, whereby the arm and stand may be adjusted one with relation to the other, substantially as will be described.

Figure 1, in elevation and section, represents part of a spinning-machine of usual 30 construction, together with a separator supported in accordance with my invention, so that the separator may be adjusted both vertically and horizontally in order to adapt 35 to the position of the spindle with relation to the roller-beam; and Figs. 2 and 3 are enlarged views of the separator, supporting-arm, and stand, together with adjusting devices therefor.

40 The roller-beam A, on which rests the usual stand to sustain usual top rolls, (not shown,) the ring-rail B, the ring C, the spindle D, the bobbin E, the step-rail F, the guide-board G, the wire-board H, having the guide-eyes J, 45 are and may be all as usual.

In accordance with my invention I have

attached the separator K, which in practice may be of any usual shape, to the supporting-arm L, the method of connection being substantially as in other separators prior to 50 this invention.

To the roller-beam A, by a screw M, I have attached a stand N. The stand N is slotted longitudinally, as at a. The supporting-arm L has a slot b, a bolt c being passed through 55 the said slots a and b. By loosening the nut d on the bolt c the arm L may be adjusted both vertically and horizontally, to thus place the separator in proper working position with relation to the spindle and bobbin, the distance of the spindle and bobbin from the roller-beam varying in different machines.

To lessen strain upon the bolt c, I have provided the arm and stand with a guiding means consisting, essentially, of a lip or rib, 65 as g, herein shown as upon the stand, which lip is adapted to enter one of a series of grooves, as f, herein shown as cut parallel to each other at the inner side of the arm L, as best shown in Fig. 3. 70

I claim—

1. A separator and its supporting-arm, the latter slotted as described, combined with the stand N slotted, as described, and with a bolt extended through the said slots, whereby the arm and stand may be adjusted one 75 with relation to the other, substantially as described.

2. The separator, the roller-beam, the slotted stand N, a slotted arm L, and separator, 80 combined with an adjusting device, as a bolt, extended through the slots in said arms, and guiding means to lessen the strain upon the said bolt, substantially as described.

In testimony whereof I have signed my 85 name to this specification in the presence of two subscribing witnesses.

GEORGE W. KNIGHT.
